UNITED STATES PATENT OFFICE.

HARRY HARTMAN, OF LOS ANGELES, CALIFORNIA.

WRIST-WATCH BRACELET FASTENER.

Application filed November 12, 1925. Serial No. 68,589.

This invention relates to improvements in wrist watch constructions.

An object of the invention is to provide a wrist watch having on its wrist encircling member a resilient link device of improved construction permitting the wrist encircling member to accommodate itself to the wrist.

Another object of the invention is to provide an improved fastener construction by which an end of the wrist encircling member may be attached to the bail of a wrist watch.

A further object of the invention is to provide a construction in which the fastener and the resilient link are combined upon the same body, permitting chains, ribbons, straps and other devices to be employed as wrist encircling members.

With the foregoing and other objects in view which will be made manifest in the following detailed description and specifically pointed out in the appended claims, reference is had to the accompanying drawings for an illustrative embodiment of the invention, wherein:

24. Figure 1 is a perspective view of a wrist watch illustrating the part embodying the invention, as mounted thereon,

Fig. 2 is an edge view of the part embodying the invention,

30. Fig. 3 is a front elevation of the part shown in Fig. 2, parts being broken away and shown in section, and may be considered as taken in the direction of the arrow 3 upon Fig. 2,

35. Fig. 4 is a sectional view taken on the line 4-4 of Fig. 3,

Fig. 5 is a sectional view taken substantially on the line 5-5 of Fig. 3,

40. Fig. 6 is a perspective view from the back side of the part shown in Fig. 2, this part being illustrated as having been stretched into its extreme position, and

Fig. 7 is a perspective view illustrating the fastener in open position.

45. Referring to the accompanying drawings wherein similar reference characters designate similar parts throughout, the wrist watch is indicated at W, and is provided with a wrist encircling member 10 which may be of any flexible construction, such as ribbon, chain, mesh, strap or their equivalents. Adjacent each end of the wrist encircling member 10 there is secured a part gen-

erally designated at 11, so that each end of the wrist encircling member can be detachably fastened to a bail B upon the wrist watch W. Preferably there are two of the parts 11 used, one on each end of the wrist encircling member 10, so as to present the symmetrical appearance and also to permit either end of the wrist encircling member to be detached from the watch.

The part 11 is constructed in the following manner. A front wall 12 is provided from the edges of which extend end walls 13 and 14. Back walls 15 and 16 extend toward each other but have their adjacent edges disposed in spaced relation. Intermediate walls 17 and 18 extend from the spaced edges of the back walls 15 and 16 toward the front wall 12. Another part is provided having a front wall 19 in which is formed an aperture 20 for the attachment of the wrist encircling member 10. The front wall 19 is slidable against the interior or back surface of the front wall 12, and is disposed between the front wall 12 and the edges of the intermediate walls 17 and 18. On the front wall 19 there are formed end walls 21 and 22 which are connected by a back wall 23. The end walls 21 and 22 and the back wall 23 are slidable between the intermediate walls 17 and 18. A coil spring 24 is positioned between the end walls 21 and 22 and a pin or rivet 25 passes through the side walls 13 and 14 and the intermediate walls 17 and 18 and is positioned between the end wall 21 and the end of the coil spring 24. This provides the resilient link construction for the wrist encircling member 10.

As clearly shown in Fig. 6 the front wall 19 can be withdrawn from between the front wall 12 and the intermediate walls 17 and 18 by compressing the spring 24. This spring is compressed because of its engagement with the pin or rivet 25, and by this construction it urges the front wall 19 into its normal position behind the front wall 12. The back walls 15 and 16 are joined as indicated at 26 and the back wall 26 extends beyond the ends of the end walls 13 and 14. It has its end edge bent as indicated at 27 to form a hook adapted to receive one of the bails B.

A guard member 28 has one end disposed between the side walls 13 and 14, and rigid-

ly formed with the mentioned end of the guard are two tubular members 29 forming a tubular housing which is arranged between the side walls 13 and 14 and which is rigid with the guard 28. Pintles 30 are disposed in the ends of the tubular housing so formed and extend through apertures in the side walls 13 and 14, thus pivotally connecting the sides of the guard 28 to the side walls 13 and 14. A coil spring 31 is disposed within the tubular housing and urges the pintles 30 toward their respective side walls, but permits the pintles to be pressed inwardly against the action of the spring. The ends of the pintles 30 are preferably provided with caps 32 which limit their inward movement through the side walls 13 and 14. In each of the tubular members 29 there are formed slots 33 and each pintle 20 carries an angular arm 34 which is slidable in its respective slot 33. The end of each arm 34 is capable of engaging upon the edge of its respective side wall 13 or 14, as the case may be, as shown in Fig. 7, or is adapted to enter an aperture such as is indicated at 35 in its respective side wall.

In the position shown in Fig. 7 it will be readily appreciated that when the arms 34 engage upon the edges of their respective side walls, they keep or lock the guard 28 in open position, that is, where it is disengaged from the hook 27. While in such position the hook may be caused to be slipped over a bail B. After it has been positioned upon the bail, the guard 28 can be pressed toward the hook and because of the beveled nature of the arms 34, as shown in Fig. 5, the pintles will slide inwardly against the action of the spring 31 and when the guard 28 engages the hook, as shown in Fig. 4, these angular arms 34 will enter the apertures 35, thus locking the guard in engagement with the hook 27, and preventing the bail from slipping out of the hook. In order to open the fastener so provided, the pintles are merely pressed toward each other, causing the arms 34 to be withdrawn from within the apertures 35, and in this manner the guard 28 can be swung into the open position as shown in Fig. 7, and the pintles allowed to be expanded so that the arms will engage upon the edges of the side walls 13 and 14, thus locking the guard in its open position.

From the above described construction it will be readily appreciated that an improved resilient link and fastener is provided for wrist watch encircling members which is neat and attractive in appearance and which has many advantages. It will be noted that when the front wall 19 is withdrawn from behind the front wall 12, it presents a substantially continuous appearance.

It will be understood that various changes in the detail of construction may be made

without departing from the spirit or scope of the invention as defined by the appended claims.

I claim:

1. A fastener adapted to connect a watch to a wrist band, said fastener comprising a part having a front wall, side walls, back walls extending toward each other from the side walls but having their adjacent edges disposed in spaced relation and intermediate walls extending from the adjacent edges of the back walls toward the front wall, and a second part having a front wall slidable against the back surface of the front wall of the first part, said second part having a back wall and end walls connecting the back wall to the front wall, a coil spring disposed between the end walls, means connecting the intermediate walls between one end of the spring and one end wall, thus providing a resilient link construction, and a fastener carried by one of said parts engageable upon the bail.

2. A fastener adapted to connect a watch to a wrist band, said fastener comprising a part having a front wall, side walls, back walls extending toward each other from the side walls but having their adjacent edges disposed in spaced relation and intermediate walls extending from the adjacent edges of the back walls toward the front wall, and a second part having a front wall slidable against the back surface of the front wall of the first part, said second part having a back wall slidable between the intermediate walls and end walls connecting the back wall to the front wall, a coil spring disposed between the end walls, means connecting the intermediate walls between one end of the spring and one end wall, thus providing a resilient link construction, and a fastener carried by one of said parts engageable upon the bail.

3. A fastener adapted to connect a watch to a wrist band, said fastener comprising a part having a front wall, side walls, back walls extending toward each other from the side walls but having their adjacent edges disposed in spaced relation and intermediate walls extending from the adjacent edges of the back walls toward the front wall, and a second part having a front wall slidable against the back surface of the front wall of the first part, said second part having a back wall and end walls connecting the back wall to the front wall, a coil spring disposed between the end walls, a pin passing through the side walls and through the intermediate walls, said pin being positioned between one end of the spring and one of the end walls thus providing a resilient link, and a fastener carried by one of the parts engageable upon the bail.

4. A fastener adapted to connect a watch to a wrist band, said fastener comprising a part having a front wall, side walls, back

- walls extending toward each other from the side walls but having their adjacent edges disposed in spaced relation and intermediate walls extending from the adjacent edges 5 of the back walls toward the front wall, and a second part having a front wall slideable against the back surface of the front wall of the first part, said second part having a back wall and end walls connecting the back wall 10 to the front wall, a coil spring disposed between the end walls, and a pin passing through the side walls and through the intermediate walls, said pin being positioned between one end of the spring and one of the end walls thus providing a resilient link, the back walls being extended and joined beyond the side walls and being curved to form a hook engageable upon the bail. 5. A fastener adapted to connect a watch 20 to a wrist band, said fastener comprising a part having a front wall, side walls, back walls extending toward each other from the side walls but having their adjacent edges disposed in spaced relation and intermediate 25 walls extending from the adjacent edges of the back walls toward the front wall, and a second part having a front wall slideable against the back surface of the front wall of the first part, said second part having a back wall and end walls connecting the back wall to the front wall, a coil spring disposed between the end walls, a pin passing through the side walls and through the intermediate 30 walls, said pin being positioned between one end of the spring and one of the end walls thus providing a resilient link, the back walls being extended and joined beyond the side walls and being curved to form a hook 35 engageable upon the bail, a guard having one end positioned between the side walls, means forming a tubular housing upon the mentioned end of the guard, a coil spring disposed in said housing, a pintle urged by the 40 spring into a position extending through a side wall so as to pivotally connect the guard to the side wall, and means for pivotally connecting the guard to the other side wall, said pintle carrying an angular arm 45 slideable in a slot in said housing, said arm being arranged to engage upon an edge of its adjacent side wall to keep the guard disengaged from said hook, said arm also being receivable in an aperture in its adjacent 50 side wall to keep the guard in engagement with the hook. 6. A fastener adapted to connect a watch 40 to a wrist band, said fastener comprising a part having a front wall, side walls, back walls extending toward each other from the side walls but having their adjacent edges disposed in spaced relation and intermediate 45 walls extending from the adjacent edges of the back walls toward the front wall, and a second part having a front wall slideable against the back surface of the front wall of the first part, said second part having a back wall and end walls connecting the back wall to the front wall, a coil spring disposed 50 between the end walls, a pin passing through the side walls and through the intermediate walls, said pin being positioned between one end of the spring and one of the end walls thus providing a resilient link, the back walls being extended and joined beyond the side walls and being curved to form a hook 55 engageable upon the bail, and a guard pivoted between the side walls engageable upon the hook. 7. A fastener adapted to connect a watch 60 to a wrist band, said fastener comprising a member having front, back and side walls, the back wall being extended beyond the side walls and being bent to provide a hook, a guard having one end disposed between the side walls, means providing a tubular housing upon the mentioned end of the guard, a coil spring disposed within said housing, a pintle slideable within the housing and urged into a position extending through a side wall by the spring so as to pivotally connect the guard to the side wall, and means for 65 pivotally connecting the guard to the other side wall, said pintle carrying an angular arm which is slideable in a slot in said housing and which is engageable upon the edge of the first mentioned side wall to hold the guard 70 disengaged from said hook, said angular arm being adapted to enter an aperture in the side wall to lock the guard in engagement with said hook. 8. A fastener adapted to connect a watch 75 to a wrist band, said fastener comprising a member having front, back and side walls, the back wall being extended beyond the side walls and being bent to provide a hook, a guard having one end disposed between the side walls, said pin being positioned between one end of the spring and one of the end walls thus providing a resilient link, the back walls being extended and joined beyond the side walls and being curved to form a hook 80 engageable upon the bail, a guard having one end positioned between the side walls, means forming a tubular housing upon the mentioned end of the guard, a coil spring disposed in said housing, a pintle urged by the 85 spring into a position extending through a side wall so as to pivotally connect the guard to the side wall, and means for pivotally connecting the guard to the other side wall, said pintle carrying an angular arm 90 slideable in a slot in said housing, said arm being arranged to engage upon an edge of its adjacent side wall to keep the guard disengaged from said hook, said arm also being receivable in an aperture in its adjacent 95 side wall to keep the guard in engagement with the hook. 9. A fastener adapted to connect a watch 100 to a wrist band, said fastener comprising a member having front, back and side walls, the back wall being extended beyond the side walls and being bent to provide a hook, a guard having one end disposed between the side walls, said pin being positioned between one end of the spring and one of the end walls thus providing a resilient link, the back walls being extended and joined beyond the side walls and being curved to form a hook 105 engageable upon the bail, a guard pivoted between the side walls engageable upon the hook, and means for maintaining the guard 110 in engagement with the hook. 10. A fastener adapted to connect a watch 115 to a wrist band, said fastener comprising a member having front, back and side walls, the back wall being extended beyond the side walls and being bent to provide a hook, a guard having one end disposed between the side walls, said pin being positioned between one end of the spring and one of the end walls thus providing a resilient link, the back walls being extended and joined beyond the side walls and being curved to form a hook 120 engageable upon the bail, a guard pivoted between the side walls engageable upon the hook, and means for maintaining the guard 125 in engagement with the hook. 11. A fastener adapted to connect a watch 130 to a wrist band, said fastener comprising a member having front, back and side walls, the back wall being extended beyond the side walls and being bent to provide a hook, a guard having one end disposed between the side walls, said pin being positioned between one end of the spring and one of the end walls thus providing a resilient link, the back walls being extended and joined beyond the side walls and being curved to form a hook engageable upon the bail, a guard having one end positioned between the side walls, means forming a tubular housing upon the mentioned end of the guard, a coil spring disposed in said housing, a pintle urged by the 135 spring into a position extending through a side wall so as to pivotally connect the guard to the side wall, and means for pivotally connecting the guard to the other side wall, said pintle carrying an angular arm which is slideable in a slot in said housing and which is engageable upon the edge of the first mentioned side wall to hold the guard in engagement with said hook.

side walls, means providing a tubular housing upon the mentioned end of the guard, pintles slideable in the ends of said housing and extending through the side walls, and 5 a coil spring disposed within said housing urging the pintles toward the side walls, said pintles carrying angular arms slideable

in slots in said housing, said arms being engageable upon their adjacent side walls so as to hold the guard out of or in engagement with the hook.

In testimony whereof I have signed my name to this specification.

HARRY HARTMAN.
